UNITED STATES PATENT OFFICE

ERNEST F. H. GROTHE, OF PHILADELPHIA, PENNSYLVANIA

CONNECTER PULLER FOR STORAGE BATTERIES

Application filed August 1, 1931. Serial No. 554,461.

The subject of my invention is a connector puller for separating the intercell connectors of storage batteries from the terminal posts. The intercell connectors are commonly soldered or "lead-burned" to the terminal posts. In order to separate the intercell connectors from the terminal posts it is necessary to break the seal thus formed by soldering or "lead-burning". An important feature of my invention is the provision of a cutting edge for this purpose. Preferably my cutting edge is circular in shape but it may, if desired, be notched like saw teeth.

Further features of my invention are means for creating pressure between the terminal posts and the intercell connector and means for firmly grasping the intercell connector and locating the connector puller in proper position before beginning the pulling operation.

For a further exposition of my invention reference may be had to the annexed drawing and specification at the end whereof my invention will be specifically pointed out and claimed.

In the drawing,

Figure 1 is a side elevation of my device in which the intercell connector and the terminal post are indicated diagrammatically.

Figure 2 is a bottom view of my device.

Figure 3 is a vertical cross section through the tip of the bolt member which rests on the terminal post.

Figure 4 is a side elevation of a modified form of bolt member.

In the modification of my device chosen for illustration in the drawing, there is disclosed a terminal post A of a storage battery having an intercell connector B thereon. The terminal post A and the intercell connector B are connected together by welding, soldering or "lead-burning" as indicated at C.

My improved connector puller consists of a bolt member 1 having at its lower end a cutting edge 2 and a locating member 3 as is best seen in Figure 3. The functions of these members will be explained below. Bolt member 1 also carries on a portion of its surface screw threads 4 and carries at its upper end a handle 5. Threaded on the screw threads

4 of bolt member 1 is a yoke 6 which has internal screw threads cooperating with the screw threads 4 on bolt member 1. Yoke 6 also carries external screw threads 7 on a portion of its surface. From yoke 6 there extend laterally side arms 8 having holes therein through which pass pins 9 which are retained in place by cotter pins 10 or by any other convenient means. Pivotaly mounted on yoke 6 by means of pins 9 are jaws 11 which have at their lower ends projections 12 extending towards the axis of yoke 6. At their upper ends jaws 11 carry cam faces 13.

Mounted on the external screw thread 7 of yoke 6 is carried nut 14 which has internal screw threads cooperating with the screw threads 7. Nut 14 carries on its outer surface cam face 15 which cooperates with the cam faces 13 on jaws 11.

The operation of my device is as follows: The locating member 3 is placed centrally of terminal post A and serves to retain the connector puller in proper position during the pulling operation. Jaws 11 are then placed so that projections 12 come underneath intercell connector B and rest with their front faces against terminal post A. Projections 12 have their front faces hollowed out at 16 as is best seen in Figure 2 to permit the projections 12 to more closely embrace a terminal post A and to therefore more completely underlie intercell connector B. Nut 14 is then screwed down on threads 7 so that cam face 15 coacts with cam faces 13 on jaws 11 to hold jaws 11 with the projections 12 against

the terminal post and under the intercell connector. Handle 5 is then operated causing coaction of screw threads 4 and the cooperating threads on yoke 6 so that yoke 6 is pulled up. At the same time cutting edge 2 cuts or breaks the seal C so that the intercell connector B may be drawn off terminal post A and onto the smooth portion of bolt member 1.

In Figure 4 there is disclosed a modified form of my device in which the bolt member 1 has at its lower end a cutting edge 102 having a plurality of notches 103 therein forming saw like teeth.

I do not intend to be limited in the practice

of my invention save as the scope of the prior art and of the attached claims may require.

I claim:

1. In a connector puller for storage batteries, a bolt member having at its lower end a downwardly projecting cutting edge adjacent its periphery.
2. A connector puller for storage batteries including in combination a bolt member having at its lower end a downwardly projecting cutting edge adjacent its periphery, a handle at the upper end of said bolt member, a yoke mounted on said bolt member for movement relative thereto, jaws hingedly mounted on said yoke, and a nut movably mounted on said yoke and cooperating with the ends of said jaws to adjust said jaws relative to the axis of said yoke.
3. In a connector puller for storage batteries, a bolt member having at its lower end a downwardly projecting cutting edge adjacent its periphery and a central locating member.
4. A connector puller for storage batteries including in combination a bolt member having at its lower end a downwardly projecting cutting edge adjacent its periphery and a central locating member, a handle at the upper end of said bolt member, a yoke having screw threaded engagement with said bolt member, jaws hingedly mounted on said yoke, and a nut having screw threaded engagement with said yoke and cooperating with the ends of said jaws to adjust the jaws relative to the axis of said yoke.
5. In a device for removing a connector from the terminal post of a storage battery to which it is integrally welded, the combination of a yoke member provided with means for engaging the under side of the connector and having a threaded circular opening adapted to be positioned above the terminal post when the said engaging means are in said engagement with the connector and a bolt member passing through and making threaded engagement with the walls of said opening, said bolt member having a downwardly projecting peripheral cutting edge at its lower end adapted, when the bolt member is turned and advanced through the opening, to cut a circular parting groove between the connector and the top of the post.

ERNEST F. H. GROTHE.
